UNITED STATES PATENT OFFICE.

WILLIAM UHL, OF ROCHESTER, NEW YORK, ASSIGNOR OF ONE-HALF TO HALFORD B. WARDIN, OF ROCHESTER, NEW YORK; ASSIGNOR OF ONE-HALF TO ROBERT L. FOUNTAIN PEN.

Application filed June 21, 1920. Serial No. 390,366.

To all whom it may concern:

Be it known that I, WILLIAM UHL, of Rochester, in the county of Monroe and State of New York, have invented certain new and useful Improvements in Fountain Pens; and I do hereby declare the following to be a full, clear, and exact description of the same, reference being had to the accompanying drawings, forming a part of this specification, and to the reference numerals marked thereon.

My present invention relates to fountain pens and more particularly to the feeding devices thereof whereby the ink from the reservoir is carried to the pen proper and the invention has for its object to provide an improved feeding device that will insure an adequate and uniform flow to the writing point at all times. The improvements are particularly applicable to multiple point pens having more than two tines rendering them capable of writing when held at any angle in the manner of a stylographic pen and when so embodied, the object of the invention, as above stated, is realized. To these and other ends the invention resides in certain improvements and combinations of parts, all as will be hereinafter more fully described, the novel features being pointed out in the claims at the end of the specification.

In the drawings:

Figure 1 shows a side view of a fountain pen to which my improved feeding tongue may be applied;

Figure 2 shows an enlarged section through the lower end or point of the pen shown in Figure 1, but showing the feeding point in elevation;

Figure 3 is a similar fragmentary section taken also through the feeding point;

Figure 4 is a section on the line 4^a—4^a of Figure 3;

Figure 5 is a section corresponding to Figure 3 through the point of a modified form of my invention;

Figure 6 is a section on the line 6^a—6^a of Figure 5;

Figure 7 is a section on the line 7^a—7^a of Figure 6.

Similar reference numerals throughout the several views indicate the same parts.

Referring specifically to the particular embodiment of the invention shown in the drawings, 1 indicates the tubular body or

barrel of a fountain pen and 1^a the usual cap temporarily applied, in the present instance, to the closed end. Fitting within the opposite end, preferably by a liquid-tight friction or slip joint is a plug 6 having a bore or passage 7 through its axis and terminating at its inner end in a reduced nipple 6^a to which is attached a reservoir 5 occupying the interior of the barrel 1. This reservoir, in the present instance, is of the familiar flexible or collapsible type being constituted by a rubber sack as is common in self-filling pens. The body of ink contained therein and flowing into the passage 7 is indicated at 4.

The outer end of the plug 6 is provided with a socket 7^a also axially arranged and occupied by a cylindrical tongue 8 that fits it closely and is frictionally held in place in a liquid-tight manner. It is tubular for the major portion of its length being provided with a central bore or cavity 9 that is in axial alignment and communicates with the passageway 7 of the plug. An intermediate portion of the tongue at a point 8^a within the plug socket is reduced to provide an annular socket for the reception of the tubular shank portion 9^a of a pen-point 2. This pen is in the form of a symmetrically tapered hollow shell with the three slightly rounded faces of a pyramid.

Each such side or face constitutes a separate tine, the shell being split as at 9^b along each corner of the pyramid and each tine being indicated at 3. The split portions, as usual, give flexibility to the points or tines and serve to assist the flow of ink along the interior of the pen to the writing point. Because of this multiple construction, the pen may be held at any angle during writing in the manner of a stylographic pen, that is, any one of the tines may be uppermost.

Beyond the reduced intermediate portion 8^a the feeding tongue has the same pyramidal form as pen point 2 as indicated at 10^a and fits closely within the interior of the pen point. Along its corner edges it is provided with laterally opening longitudinal slots or channels 10 that intersect the central bore 9 of the plug and also open against the inner surfaces of the pen point along and coincidently with the splits 9^b therein. Each slot becomes shallower as it progresses toward the writing point, the outer end 110

thereof being preferably a shallow groove or channel 11.

It will thus be seen that in operation the ink flows from the reservoir 5 through the passage 7 in the plug 6 and thence into the bore 9 of the feeding tongue 8, finally emerging at the outer end of the latter through the slotted channels 10. It traverses the inner surface of the pen point following the grooves 11, ultimately reaching the writing point. The capillary attraction in the channels and particularly in the small passages 11 holds back the flow until relieved by the flexing of the tines 3 and prevents flooding.

In the embodiment of the invention shown in Figures 5, 6 and 7, the central bore 9 within the shank of the tongue 8 is omitted and instead, the laterally opening longitudinal channels are slotted the full length of the tongue, as indicated at 13. The bottom of the socket 7^a is flared or enlarged, as shown at 14, and this permits the passage 7 to communicate directly with the slotted channels 13 and to deliver the ink through a greater length of channel to the writing point.

The parts of the pen embodying my invention may be readily turned separately and easily assembled or taken apart and the forming of the feed channels 10-11 is a simple operation resulting from a single cut of a milling tool before or after the center bore 9 has been drilled.

I claim as my invention:

1. In a fountain pen, the combination with a barrel having an ink reservoir therein and a writing point split to form a plurality of tines, of a feeding tongue having a longitudinally extending interior cavity communicating with the reservoir and also provided with a laterally opening longitudinal channel intersecting the outer extremity of the cavity at one end of the slot and extending to the inner surface of the writing point, the other or outer end of the slot being relatively shallow and constituting a channel leading along the surface of the tongue to the tip of the writing point.
2. A feeding tongue provided with a pyramidal taper having channels along the edges of said taper and extending down to the apex of the point.

WILLIAM UHL.
